UNITED STATES PATENT OFFICE

GEORGE W. REASOR, OF LOS ANGELES, CALIFORNIA

DESIGN FOR A VENDING-MACHINE CABINET

Application filed November 3, 1930. Serial No. 37,519. Term of patent 7 years.

To all whom it may concern:

Be it known that I, GEORGE W. REASOR, a citizen of the United States, residing at Los Angeles, in the county of Los Angeles and State of California, have invented a new, original, and ornamental Design for Vending-Machine Cabinet, of which the following is a specification, reference being had to the accompanying drawing, forming a part thereof.

In the accompanying drawing

Fig. 1 is a front view of the vending machine cabinet showing my new design and Fig. 2 is a side view of the same.

I claim:

The ornamental design for a vending machine cabinet, substantially as shown.

GEORGE W. REASOR.
